INDICATING DEVICE FOR INDICATING THE
NEXT DEALER IN A CARD GAMEArthur F. Faber, Erie, and Carter D. Ellis,
Fairview Township, Erie County, Pa.

Application February 14, 1948, Serial No. 8,484

14 Claims. (Cl. 116—133)

1

This invention relates generally to indicating devices and more particularly to devices for indicating the person who is the next dealer in a card game.

The argument as to who is the next dealer in a card game, especially when four or six talkative people are playing, is a perpetual one. Indicating devices have been provided to indicate the next dealer in a card game by directing arrows but these have required manual manipulation aside from the manipulation of the pencil to keep the scores thereby making these indicating devices of little use and they have never been accepted by the card playing public for this reason.

It is, accordingly, an object of my invention to overcome the above and other defects in indicating devices for indicating the next dealer in a card game and it is more particularly an object of my invention to provide an indicating device for indicating the next dealer in a card game which is simple in construction, economical in cost, economical in manufacture, efficient in operation and simple and easy to operate.

Another object of my invention is to provide an indicating device for indicating the next dealer in a card game which permits the manipulation of a device with a pencil being utilized for keeping the tally or score of the game.

Another object of my device is to provide an indicating device for indicating the next dealer in a card game which permits the use of a pencil for operating the device and also provides a holding means for the pencil.

Another object of my invention is to provide an indicating device for indicating the next dealer in a card game wherein provision may be made when double scores are kept.

Another object of my invention is to provide an indicating device for indicating the next dealer in a card game which may be utilized for 2, 3, 4, or 6 players or any variation thereof.

Another object of my invention is to provide an indicating device for indicating the next dealer in a card game which is positive in operation and which is simple and easy to read.

Other objects of my invention will become evident from the following detailed description, taken in conjunction with the accompanying drawings, in which

Fig. 1 is a perspective view of my novel indicating device for indicating the next dealer in a card game;

Fig. 2 is a developed view of the cylinder used in my novel device for indicating the next dealer in a card game;

2

Fig. 3 is a transverse sectional view taken through the axial center line of the head of my novel indicating device for indicating the next dealer in a card game;

Fig. 4 is a vertical sectional view longitudinally of my device showing the end of the indicating drum and the dog adapted to be engaged therewith;

Fig. 5 is a fragmentary developed view of the movable shielding member for covering the indicating numerals under certain predetermined windows of my novel device; and

Fig. 6 is a fragmentary vertical sectional view of one end of my novel indicating device for indicating the next dealer in a card game; and

Fig. 7 is a transverse fragmentary sectional view showing the dog engaging the grooved end of the indicating drum of my novel indicating device for indicating the next dealer in a card game.

Referring now to Figs. 1, 3 and 4, I show a casing 1 having a semi-circular shaped, transverse, upwardly extending portion 2 with four windows 3a, 3b, 3c and 3d, a slot 4 and a tapered platform or table 5 for mounting or attaching thereto a tally 6. The end portions 7 and 8 of the arcuate shaped end 2 of my device has apertures 39 and 40 for journaling a shaft 11 which has attached to one end thereof a handle 12 with a locking screw 13. A bushing 9 is disposed in the aperture 39. A drum 14 is formed on flange members 15 and 16 which are mounted on shaft 11 and flange member 15 is fixed thereto by the apertured hub 17 and cotter pin 18 extending transversely through an aperture 19 in the shaft 11. A marginal edge 20 of the drum 14 is divided into 24 semi-circular shaped, equally spaced, adjacently disposed grooves 21 as is particularly shown in the developed drum 14 shown in Fig. 2. It will be evident that there may be any multiple of 24 grooves if desired. The surface of the drum 14 has circumferentially aligned, spaced numerals in columns 41, 42, 43 and 44 aligned with the windows 3a, 3b, 3c and 3d in the portion 2 of the outer casing 1 to provide for variation in the number of players from 2 to 6.

A brake member 22 is mounted in axial alignment with the drum 14 on the shaft 11 and one side thereof is urged into engagement with the flanged brake shoe 23 by spring member 24 which engages hubbed brake member 22 and the stop member 26 secured on the shaft 11 by locking screw 27. The brake member 22 has a hubbed portion 28 with apertures 29 for receiving a key or pin 30 which extends through a slot 60 in

the shaft 11. The brake member 22 is held against relative rotation with the shaft 11 but limited longitudinal movement thereof is provided. The brake member 22 is loosely mounted on the shaft 11 so that slight tilting is provided wherein the portion of the brake member 22 opposite to the shoe 23 will normally engage the end 20 of the drum 14. An arcuate shaped shielding member 31 is disposed a spaced distance from the outer side of the drum 14 and adjacent the inner periphery of the arcuate shaped portion 2 of the casing 1 and it is held in position by headed guide members 32 movable in spaced slots 33 in the arcuate shaped portion 2 of the casing 1. The member 31, which is shown in the fragmentary view in Fig. 5 in a developed position, has spaced circumferentially aligned apertures in four columns 34, 35, 36 and 37 coinciding with columns 41, 42, 43 and 44 on the drum 14. The apertures in columns 35 and 37 are aligned transversely and the apertures in columns 34 and 36 are offset from the apertures in columns 35 and 37 but aligned transversely with each other. This transverse alignment holds true for the numerals in columns 41 and 43 and 42 and 44. An upwardly extending bracket 38 is provided to rotate the shielding member 31. The bracket 38 is arcuate in shape to coincide with the grooves 21 to receive and guide a pencil. The forward end of the bracket 38 provides a terminal point and arcuate grooved guide for the pencil 50 in its entry into the arcuate grooves 21 upon rotation of the drum 14. The number of players are indicated by the numerals 53 adjacent to the windows 3a, 3b, 3c and 3d and the dealer scheduled to deal in a four handed game would be shown in Fig. 1 at 54.

A gravity operated counterweighted dog 89 is pivoted centrally thereof on the brake shoe 23 at 47 and the end 40 thereof engages the marginal grooved end 20 on the drum 14 to limit the movement thereof to one direction. The end 40 of the dog 89 progressively moves into each successive groove 21 on the marginal end 20 of the drum 14 when the drum 14 is rotated by a pencil or other elongated member so as to prevent any counterrotation of the drum 14 after it is rotated to a predetermined position, the counterweighted portion of the dog 89 continually urging the end 40 thereof into the grooves 21 on the end 20 of the drum 14.

In operation, setting indicia 55 is provided adjacent the slot 4 thereby permitting the selection of the proper indicia on the drum 14 by merely disposing the face of the bracket 38 adjacent the selected indicia 55 which may be for two or four players, three or six players or for four or two players double or six and three players double. When the face of the bracket 38 is disposed in the position as shown in Fig. 1, the drum may be rotated six spaces or the distance covered by six arcuate shaped grooves 21 or a quarter turn of the drum 14. Since the numerals in column 41 are spaced a quarter turn on the drum 14, provision is thereby made for the numerals 1 and 2 to appear before window 3a on the left end of the arcuate shaped portion 2 of the casing 1 alternatingly. If four players are playing, then column 43 is utilized wherein the numerals 1, 2, 3, and 4 are spaced a quarter turn circumferentially around the drum so that they appear successively in the window 3c in the arcuate shaped portion 2 of the casing 1. Shielding member 31

will be in a position wherein the apertures in column 34 and 36 will lie in registry with the windows 3a and 3c in the arcuate shaped portion 2 of the casing 1 so as to expose the indicia in columns 41 and 43 on the drum 14. When the face of the bracket 38 is pulled forwardly two grooves to a position adjacent the setting indicia 3-6, the drum 14 is then in a position to rotate a distance covered by four grooves 21 or one sixth of a turn of the drum 14. Since the numerals in columns 42 and 44 are spaced one sixth of a turn apart circumferentially around the drum 14, a numeral will appear in windows 3b and 3d on each one sixth turn of the drum 14 by the pencil 50 in engagement with the grooved portions 21 of the drum 14. When three players are playing, window 3b is utilized so that numerals 1, 2, and 3 appear successively. Where six players are playing, the numerals 1 to 6 in column 44 appear successively in the window 3d. When the bracket 38 is in a position adjacent the 3-6 indicia, then the apertures in columns 35 and 37 in the shield 31 register with the windows 3b and 3d thereby exposing numerals in columns 42 and 44 on the drum 14. By moving the bracket 38 adjacent the indicia 4-2 double, the pencil 50 is removed twice between deals thereby requiring a double rotation of the drum 14 a distance of three grooves each or one quarter of a turn. When the bracket 38 is adjacent 6-3 double, the drum 14 is given a double rotation of 2 grooves each or one sixth of a turn. After my device is set as desired, the pencil 50 is extended into the groove 21 adjacent the bracket 38 thereby moving the upper end of the brake member 22 away from the brake shoe 23. The pencil 50 gravitates downwardly to the lower end of the slot 4 to a position as shown in Fig. 1. This operation is repeated after each score is noted.

In Figs. 6 and 7, I show the braking disk or member 22 with the upper end engaging the brake shoe 23 and the lower end engaging the marginal edge 20 of the drum 14. The spring 24 urges the brake member 22 against the brake shoe 23 and the end 20 of the drum 14. When a pencil 20 or a like elongated instrument is inserted through the slot 4 into engagement with one of the grooves 29 on the end of the drum 14, the upper end of the brake member 22 is moved away from the brake shoe 23 against the force of the spring 24. Upon the rotative movement of the pencil 50 in the slot 4 when in engagement with arcuate shaped grooves 21 on the drum 14, the brake member 22 is rotated with the drum 14 inasmuch as the brake member 22 is in frictional engagement with the end of the drum 14 and out of engagement with the brake shoe 23. The pin 30 movable in the elongated slot 60 in the shaft 11 permits limited longitudinal movement of the brake member 22 and fixes the brake member 22 against relative rotational movement with respect to the shaft 11. The pin 30 is secured to the hub 28 of the brake member 22. It will be noted that the brake member 22 has a slight tilting movement in that it is loosely mounted on the shaft 11. The stop member 26 having a locking screw 27 for locking it on the shaft 11 is adjustable longitudinally on the shaft 11 to vary the tension of the spring 24 and, therefore, the force of the brake member 22

against the brake shoe 23 and the end of the drum 14.

It will be evident from the foregoing description that I have provided a novel indicating device for indicating the next dealer in a card game which provides for games of cards with two to six players and also provides for a situation where it is necessary to score points in the game twice between deals, which provides a convenient holder for a pencil and which reduces to a minimum the possibility of carelessness.

Various changes may be made in the specific embodiment of my invention without departing from the spirit thereof or from the scope of the appended claims.

What we claim is:

1. An indicating device for indicating the next dealer in a card game comprising an arcuate shaped casing having longitudinally spaced windows, a drum rotatably mounted in said casing having spaced, circumferentially aligned indicia in alignment with said windows, said drum having circumferentially spaced marginal grooves on one end thereof adapted to be engaged by an elongated member to rotate same, a spring-urged disk frictionally engaging a portion of the end of said drum, and a brake shoe for engaging a portion of said disk, said disk being movable away from said brake shoe by said elongated member upon engaging a groove on the end of said drum whereby said drum may be rotated a predetermined amount to selectively expose predetermined indicia in said windows.

2. An indicating device as set forth in claim 1 wherein an apertured shield is rotatably mounted adjacent said windows to selectively shield them.

3. An indicating device as set forth in claim 1 wherein a hinged dog progressively engages the circumferentially spaced marginal grooves on the end of said drum to limit the movement thereof in one direction.

4. An indicating device as set forth in claim 1 wherein there are multiples of 24 grooves.

5. An indicating device for indicating the next dealer in a card game comprising an arcuate shaped casing having spaced windows and a circumferentially extending slot, a drum rotatably mounted in said casing having one marginal end thereof adjacent said slot with circumferentially spaced grooves, said spaced, arcuate shaped grooves being engageable by an elongated instrument extending through the slot in said casing to rotate said drum, circumferentially aligned indicia in alignment with said windows in said casing, means for covering a predetermined portion of said slot to limit the rotational movement of said drum by said elongated member, and a spring-urged brake having a portion thereof engaging said drum, said brake being releasable by said elongated instrument when it is engaging the grooves in the end of said drum whereby said drum may be rotated a predetermined amount to selectively expose predetermined indicia in said windows.

6. An indicating device as set forth in claim 5 wherein a shielding member is disposed for rotation in said arcuate shaped casing for selectively shielding the windows of said casing.

7. An indicating device as set forth in claim 6 wherein a dog is hingedly mounted on a bracket to engage said arcuate shaped marginal portion

of said drum to limit the movement thereof in one direction.

8. An indicating device for indicating the next dealer in a card game comprising an arcuate shaped casing having spaced windows and a slot, a rotatable drum mounted in said arcuate shaped casing having arcuate shaped, spaced, grooved marginal portions on the edge thereof adjacent the slot in said casing, a shield movable in said casing for selectively shielding said windows therein, spaced indicia on said drum in circumferential alignment with said windows for selectively indicating the next dealer in a card game, brake means for said drum comprising a brake member having a portion thereof in frictional engagement with the end of said drum, and a dog for limiting the movement of said drum in one direction, said arcuate shaped marginal grooves on the edge of said drum being engageable by an elongated instrument extending through the slot in said casing to rotate said drum to selectively expose the indicia thereon in said windows and to release said brake means.

9. An indicating device as set forth in claim 8 wherein circumferentially spaced-setting indicia is disposed adjacent said slot.

10. An indicating device as set forth in claim 8 wherein said shielding means has an arcuate shaped bracket extending upwardly in said slot in said casing for covering a predetermined number of grooves to limit the rotation thereof.

11. An indicating device for indicating the next dealer in a card game comprising a casing having spaced windows and a slot, a rotatable drum mounted in said casing having arcuate shaped, spaced, grooved marginal portions on one end thereof adjacent said slot, spaced indicia on said drum in circumferential alignment with said windows for selectively indicating the next dealer in a card game, a brake member for engaging said drum, said brake member being movable with said drum rotatively and movable a limited amount longitudinally relative to said drum, and a brake shoe for engaging one side of said brake member, said brake member being movable away from said brake shoe by an elongated instrument extending into the slot in said casing to engage said grooved portions of said drum to rotate same.

12. An indicating device as set forth in claim 11 wherein said slot is offset on one side of said casing so that an elongated member extending therethrough into said grooves on said drum will gravitate downwardly.

13. An indicating device for indicating the next dealer in a card game wherein single or double tallies are made comprising a rotatable member having aligned indicia thereon, selective means for rotating said rotatable member a predetermined amount, an adjustable shielding member for selectively shielding the indicia on said rotatable member and means associated with said shielding member for limiting the movement of said selective means whereby a predetermined indicia may be selected upon a predetermined rotation of said rotatable member on a single tally between deals and the same predetermined indicia may be selected by multiple rotation of said rotatable member upon a multiple tally between deals, means for rotating said rotatable member and releasable brake

means for holding said rotatable member and brake means in a predetermined position.

14. An indicating device for indicating the next dealer in a card game comprising an arcuate shaped casing having spaced windows and a circumferentially extending slot, a drum rotatably mounted in said casing having spaced, circumferentially aligned indicia in alignment with said windows, a spring-urged brake member engaging one end of said drum, and means on said drum engageable by an elongated member extending through the slot in said casing for rotating said drum, said elongated member releasing said brake member upon engagement with said rotating means on said drum.
